To all whom it may concern:

Be it known that we, Ralph O. Munson, a citizen of the United States, residing at Chicago, in the county of Cook and State of Illinois, and Robert Nerem, a citizen of the United States, residing at Evanston, in the county of Cook and State of Illinois, have invented a new, original, and ornamental Design for a Service Station Building or the like, of which the following is specification, reference being had to the accom-

panying drawing, forming part thereof, in which:

Figure 1 is a perspective view of a service station building according to our new design; and

Figure 2 is a horizontal section of the service station building shown in Figure 1.

We claim:

The ornamental design for a service station building or the like, substantially as shown.

RALPH O. MUNSON.
ROBERT NEREM.
